UNITED STATES PATENT OFFICE.

AUGUST SUNDH, OF HASTINGS-UPON-HUDSON, NEW YORK.

WINDOW-CLEANING DEVICE.

1,346,348.

Specification of Letters Patent.

Patented July 13, 1920.

Application filed December 30, 1918. Serial No. 269,019.

To all whom it may concern:

Be it known that I, AUGUST SUNDH, a citizen of the United States, and a resident of Hastings - upon - Hudson, Westchester county, State of New York, have invented certain new and useful Improvements in Window-Cleaning Devices, of which the following is a specification.

My invention relates to an improved glass cleaning device particularly adapted for windows, wind-shields and the like, and comprising means whereby the same may readily be kept clean and free from moisture, snow, ice, etc.

15 The invention is especially adapted for use on transportation vehicles such as street cars, railroad locomotives, automobiles and the like, where the vision of the driver, for safety's sake, must be unobstructed.

20 To this end I have provided means whereby the glass or wind-shield may be heated to prevent accumulation of snow and ice thereon, and additional means whereby moisture and dirt which may accumulate on the glass 25 may be blown therefrom by a blast of compressed air supplied from any suitable source. In cold weather the heating device may be kept running continuously, if desired, while the air blast may be used as 30 often as necessary, the control therefor being placed within convenient reach of the operator.

In general, my device comprises a pipe connected for convenience to the compressed 35 air tank supplying compressed air to the brakes of the car, this pipe being located at or near the upper part of the window to be cleaned and being provided with a longitudinal slot extending practically the entire 40 width of the window, means having been provided whereby the pipe in which the slot is cut may be rotated to vary the angle of inclination at which the air blast will be imposed upon the surface of the glass. In 45 addition I provide a heating device comprising a resistance element connected to the source of supply which furnishes the power for operating the air pump by which the air in the tank is compressed.

50 To carry out my invention I will use compressed air from a suitable source and if said source is not available I will provide a power-driven air compressor as it is necessary to have quite a high pressure for obtaining good results.

In the accompanying drawings, wherein I

have shown the preferred embodiment of my invention,—

Figure 1 is an elevational view of the front part of a car with my window cleaning device applied thereto; and

Fig. 2 is a sectional elevational view of the showing in Fig. 1.

Referring to the drawings in detail, 1 designates a car or other transportation vehicle having a window 2 which it is desired to have kept clean. At the bottom of the car I have shown an electric motor 3 and operating an air compressor 4 for supplying air under pressure to a tank 5, which 60 air is usually employed for operating the air-brakes (not shown) of the car. Leading from the tank 5 upwardly to the upper part of the window 2 is a pipe 6 communicating with a short length of pipe 7 located at the 65 upper part of the window and extending transversely thereof. The pipe 7, it will be observed from Fig. 2, is located slightly in advance of the front of the window and is provided with a slot 8 therein, which is 70 preferably cut longitudinally of the pipe and extends the entire width of the window. From Fig. 2 it will be observed that this slot is at an angle to the face of the window and in order that this angle of inclination may 75 be varied as desired, I have provided a hand-wheel 9, in Fig. 1, by which the pipe 7 may be rotated. The passage of air under pressure from the tank 5 to the pipe 7 is controlled by a valve 10 operable by a pedal 11 80 which is placed within easy reach of the operator of the vehicle.

From the description thus far given it will be seen that a blast of air under pressure may be imposed upon the outer surface of the window 2 at an angle thereto inclined in the direction of gravity. I preferably place the pipe 7 at the upper part of the window inasmuch as I am then able to take advantage of the natural flow of moisture from the window under the action of gravity.

From Fig. 2 it will be observed that the window comprises inner and outer panes, 12 and 13, respectively, spaced from each other to provide a chamber 14. Below the window I provide a compartment 15 leading to the chamber 14 and in which compartment I place a resistance element 16. This resistance receives its energy from the source 95 of supply furnishing power to the motor 3, this supply being controlled by switches 100 110 17.

and 18. With these switches closed the resistance element 16 will receive current and be heated up to heat the air in the chamber 14 and thereby heat the window-pane 13. 5 This heating element has been provided for the purpose of maintaining the window 2 slightly warm so that snow and ice striking the same will be melted and the resulting moisture may be then easily blown from the 10 window by the air blast already referred to. Obviously the heating of the window may be regulated as desired and also, if the vehicle to which my device is applied be used where the temperature of the atmosphere is always 15 above the freezing point, the heating element may be dispensed with entirely and the window cleaned by the compressed air solely.

If found more convenient the heating element 16 may be dispensed with even in cold 20 weather, but in such an event it would be preferable to heat the air blast. I believe, however, that such an arrangement would not be as satisfactory as that which I have 25 herein illustrated and described, and would probably require more power.

It will be obvious that various changes 30 may be made in the details of construction and arrangement of parts herein illustrated and described to suit varying conditions without departing from the spirit and scope of my invention, and I desire, therefore, not to be limited to the precise arrangement of parts illustrated.

35 What I claim as new and desire to secure by Letters Patent of the United States is:—

1. A window-glass cleaning device comprising means for heating the surface of the glass and means for imposing a blast of compressed air upon the heated surface to 40 clean the same.

2. A window-glass cleaning device comprising means for imposing a blast of com-

pressed air upon the surface of the glass and at an angle thereto, which is inclined 45 toward the direction of the lower edge of the glass, and means for varying the inclination of the air blast to the surface of the glass.

3. A window-glass cleaning device comprising heating means at the lower part of 50 the glass for heating the surface of the same, and means at the upper part of the glass for imposing a blast of compressed air upon the heated surface of the same, said air blast being imposed downwardly upon the glass 55 surface and at an incline thereto.

4. A window-glass cleaning device comprising a pipe having a longitudinal slot therein, means connecting the pipe to a supply of compressed air whereby a blast of 60 compressed air may be imposed upon the surface of the glass to be cleaned and at an angle thereto, and means for varying the position of the slot in the said pipe relatively to the surface of the glass whereby the 65 angle of inclination of the air to the glass surface may be varied.

5. A device for cleaning window-glass having inner and outer panes, comprising a heating device communicating with the 70 chamber between the said inner and outer panes, whereby the outer pane will be heated, and means for imposing a blast of compressed air against the outer surface of said outer pane to clean the same. 75

6. A window-glass cleaning device comprising a pipe having a longitudinal slot therein through which a blast of compressed air is imposed upon the surface of the glass and at an angle thereto, which angle is inclined downwardly, said pipe being movable to vary the inclination of the air blast to the surface of the glass. 80

This specification signed this 28th day of December, A. D. 1918.

AUGUST SUNDH.
